OLIVER S. JENNINGS, OF BROOKLYN, NEW YORK, ASSIGNOR TO WESTINGHOUSE ELECTRIC & MANUFACTURING COMPANY, A CORPORATION OF PENNSYLVANIA.

SWITCH MECHANISM.

Application filed December 2, 1920. Serial No. 427,776.

- My invention relates to switches and particularly to snap-action enclosed switches such as are used for controlling lighting and power circuits.
- 5 An object of this invention is to provide a switch mechanism wherein the arcs usually incident to the interruption of a loaded circuit are extinguished before the switch elements are injured.
- 10 Another object is to provide a switch mechanism wherein controlling means in the form of a barrier serves to extinguish the arcs incident to the opening of a loaded circuit.
- 15 Another object is to provide a switch mechanism having the above characteristics wherein the barrier serves as a shield for preventing access to the live switch-jaw members of the switch mechanism.
- 20 A further object is to provide a simple, effective and inexpensive method of extinguishing the electric arcs incident to the separation of the contact members of the switch mechanisms.
- 25 It is a well-known phenomenon that, when the switch members are withdrawn from engagement with the contact-jaw members, destructive arcing results. The life of the arc thus produced has been reduced by opening the switch elements with a rapid or snap action. This method does not entirely eliminate the arcs and the switch elements gradually become pitted and unserviceable as a result of repeated opening operations.
- 30 To obviate this difficulty and to extinguish the arc before it has an opportunity to attain an injurious magnitude and temperature, I have provided a slotted barrier through which the movable switch element
- 35 passes in its opening movement. The barrier is so arranged immediately adjacent the stationary switch-jaw members that the contacting portion of the switch-blade member, upon disengagement from the switch-jaw member, passes immediately through the slot in the barrier and draws the arc into the slot where it is extinguished in a manner to be more fully hereinafter explained.
- 40 The barrier is disposed between the opening in the housing and the permanently-charged switch-jaw member and serves as a shield for preventing access to the live-jaw members through the opening in the cover.

The objects above defined, as well as others 55 that will be apparent throughout the further description of the invention, are attained by means of the switch mechanism hereinafter described and illustrated in the accompanying drawings, wherein:

60 Figure 1 is a plan view of the apparatus shown installed in a housing, from which the cover has been removed.

Fig. 2 is a vertical longitudinal section through the housing shown in Fig. 1, showing the switch mechanism in side elevation.

Referring to the drawings, the apparatus includes a metal housing provided with a detachable cover portion 4 having a hinged door 5 for closing an opening in the cover. 70 The switch mechanism is mounted upon an insulating base or panel 6 that is secured to the bottom of the housing. Upon this base is mounted three separate sets of stationary switch-jaw members, each set consisting of aligned jaw members 7 and 8 that are arranged in spaced relation.

75 Between the jaw members 7 and 8 a switch shaft 9 is journaled for rotation. This shaft carries a knife-blade member 10 for each set 80 of jaw members, with which the blade members are designed to engage when in a horizontal position. When the switch-blade members are in vertical position, they are out of engagement with the jaw members.

85 The shaft 9 is rotated by means of a shaft 11 which projects exteriorly of the housing from the side thereof and is provided with a suitable handle, not shown. Switch-operating mechanism 12 is provided within a compartment 13 for the purpose of so imparting movement to the switch-blade members that a predetermined turning movement of the shaft 11 causes the switch-blade members to be moved into or out of engagement 90 with the switch-jaw members 7 and 8 with a snap action. A description of the details of this actuating mechanism will not be herein recited because the specific actuating mechanism constitutes no part of this invention and any desired form of switch-actuating mechanism may be employed.

95 The live conductors, not shown, entering the box 3 are attached to the binding screws 14, and the current applied from the conductors is conducted through the switch jaws 7, the switch blades 10, the switch-jaw members 8, the conducting strips 15, the fuse clips 100

16 attached thereto, the fuse members 17 mounted within the clip 16, the fuse clips 18 and terminals 19.

The fuse members 17 are disposed directly beneath the opening in the cover 4 and are, therefore, accessible through the said opening. The circuit through the switch mechanism is such that, when the switch-blade members are in open position, the terminals 19 only have voltage impressed thereon.

A baffle wall or barrier 20, preferably made of refractory heat-absorbing insulated material, is disposed immediately adjacent the switch-jaw members 7 and between the 15 said jaws and the switch shaft 9. The barrier extends transversely of the housing 4 and prevents access to the live terminals through the opening in the cover.

Vertically disposed parallel slots 21 are 20 provided in the barrier through which the switch-blade members 10 operate. These slots are of just sufficient width to clear the blades, and the thickness of the barrier is such that an extensive area of heat-absorbing 25 material is presented adjacent the sides of the blades and in the vicinity of the final point of separation of the switch-blade member and the switch-jaw member. The barrier serves the two-fold purpose of shielding 30 the live switch-jaw members 7 from access thereto through the opening in the cover and of extinguishing the sparks incident to the separation of the switch-blade members from the switch jaw members.

35 The manner in which the arcs are extinguished is as follows: When the blade members are moved out of engagement with the jaw members, the outer ends of the blade members pass directly through the slots 21. 40 The arcs incident to the separation of the blades from the jaw members come into contact with the heat-absorbing or cooling walls of the slots in the barrier, whereby the temperature thereof is reduced and the arcs are, 45 consequently, extinguished.

This cooling action is facilitated for the reason that the arcs are drawn into the slots, which flatten them and prevent their expansion except in the plane of the slots. Thus, 50 the areas of the arcs exposed to the cooling action of the walls of the slots are increased and the heat absorption thereby is facilitated.

55 Further, the action of drawing the arcs into a confined space increases the velocity of the gases of combustion which tends to blow the sparks away from their respective terminals. There are, no doubt, disturbing influences set up by the entrance of the 60 spark into a confined space, aside from those enumerated above, that facilitate the extinction of the arcs and it has been found that the barrier herein provided serves to successfully and positively extinguish arcs produced by loads that are many times the

rated capacity of the switch mechanism with which it is associated.

It will be understood that the barrier, as shown, may be applied to a great variety of types and forms of switches with equal 70 effect, and that the form of barrier may be altered to suit the requirements of the apparatus to which it is applied without departing from the spirit of my invention.

While I have described and illustrated 75 but one embodiment of my invention, it will be apparent to those skilled in the art that various changes, modifications, substitutions, additions and omissions may be made in the apparatus described without departing 80 from the spirit and scope of the invention, as set forth in the appended claims.

I claim as my invention:

1. The combination with a switch-jaw member and a snap-switch member spaced 85 from and movable into and out of engagement with the jaw member with a snap action, of a transverse barrier disposed between the axis of rotation of the switch member and the jaw member and provided with 90 an aperture through which the movable member operates.

2. The combination with a switch-jaw member and a rotary switch member spaced 95 therefrom and movable into and out of engagement with the jaw member, of a transverse barrier disposed between the axis of rotation of the switch member and the jaw member and provided with an aperture 100 through which the switch member operates in moving into or out of engagement with the jaw member.

3. The combination with a pair of spaced switch-jaw members and a rotatable switch member for connecting the said jaw members, of a transverse barrier disposed 105 between the said jaw members and provided with an aperture through which the said switch member operates in moving to open position.

4. Switch mechanism comprising a housing having an opening therein, a switch-jaw member within the housing, a rotatable switch member within the housing, movable into engagement with the said jaw member, 115 and a transverse barrier disposed within the housing between the jaw member and the said opening and between the jaw member and the axis of rotation of the switch member for preventing access to the said jaw member through the said opening, the said barrier being positioned between the switch member and the said jaw member and provided with an aperture through which the switch member operates in moving to open 120 position.

5. The combination with a switch-jaw member and a rotary switch having blade members successively engaging the said jaw member when the switch is rotated in a 130

single direction, of a transverse barrier between the axis of rotation of the switch and the said jaw member having an aperture through which the blade members successively operate in moving into and out of engagement with the jaw member.

6. Switch mechanism comprising a housing, a contact member within the housing, a switch member rotatably movable into engagement with the contact member, and a transverse barrier within the housing disposed between the contact member and the axis of rotation of the switch member and having an aperture through which the switch member operates in moving from engagement with the contact member.

7. The combination with a switch jaw member and a rotary switch member spaced therefrom and movable into and out of engagement with the jaw member, of a trans-²⁰ verse barrier disposed between the axis of rotation of the switch member and the jaw member and provided with an aperture through which the switch member extends when in operative relation to the jaw member and through which the switch member operates in moving to open position.

In testimony whereof, I have hereunto subscribed my name this 5th day of November, 1920.

OLIVER S. JENNINGS.
